UNITED STATES PATENT OFFICE.

ELIAS ZARAGOZA, OF MANILA, PHILIPPINE ISLANDS.

ELECTRIC-SWITCH MECHANISM.

Application filed November 29, 1921. Serial No. 518,724.

To all whom it may concern:

Be it known that I, ELIAS ZARAGOZA, a citizen of the United States, residing at Manila, in the Philippine Islands, have invented certain new and useful Improvements in Electric-Switch Mechanisms; and I do hereby declare the following to be a full, clear, and exact description of the invention, such as will enable others skilled in the art to which it appertains to make and use the same.

The object of the invention is to provide a simple inexpensive and efficient switch mechanism which by various arrangements of the parts is adapted to perform the functions of a circuit breaker, a circuit closer, a vibrator, a current limiter, a relay or a repeater, and wherein the use of pivoted members and others involving the factor of friction are eliminated and the construction and arrangement of the parts is such as to afford the maximum sensitiveness, delicacy and refinement in operation while the possibility of disarrangement or displacement of the parts under service conditions is minimized; and with these objects in view the invention consists in a construction, combination, and relation of parts of which a preferred embodiment is shown in the drawings, wherein—

Figure 1 is a side view, and

Figure 2 is an end view of a switch embodying the invention,

Figure 3 is a plan view of the same,

Figures 4 and 5 are end and plan views showing a rearrangement of the parts to adapt the structure for use as a circuit closer,

Figures 6, 7 and 8 are detail views of the carrier for the vibrator or tongue,

Figure 1^a is a side view and Figure 2^a is an end view of a modified construction of the switch,

Figure 3^a is a plan view of the same,

Figure 4^a is a side view showing an arrangement of the parts to adapt it for use as a circuit closer.

In the form of the invention which is illustrated in Figures 1 to 3 inclusive, the magnet 10 is of U-shape or form having a U-shaped core 11 engaged by the spool or winding 12 and the opposite poles 13 and 14 of which, when the device is arranged in the vertical position indicated in the drawings, the arm or pole 14 constitutes a base for attachment to a suitable support and

as a support for the vibrator or tongue 15. This vibrator or tongue, of elastic or resilient material and preferably of a sensitive quality, either constitutes the armature or 60 may carry a soft metal armature 16 as shown in the drawings, said tongue or vibrator being attached at one end to the flange 17 at one end of a carrier 18 which is adjustably mounted upon the foot 14 to provide for 65 varying the position of the tongue or vibrator. In the construction illustrated this carrier consists of a plate slotted as shown at 19 for engagement by the binding screw 20 and having a depending flange 21 bearing 70 against the edge of the foot to guide the plate or carrier in its adjustment and insure a proper positioning of the tongue or vibrator.

Whether the tongue or vibrator constitutes the armature or carries an armature 16 as illustrated, there are provided contacts 23 and 24, either of which may be employed at the option of the operator and in accordance with the purpose for which the 75 switch is to be used, and if to be used as a circuit breaker, the contact 24 is arranged in operative relation with a contact 25 which is carried by a support 26 preferably adjustably mounted upon a post 27 or its 80 equivalent and adapted to be moved toward and from the contact 24 according to the strength of current which should be carried or conveyed from the contact 24 to the contact 25 without the breaking of the circuit, 85 it being obvious that if the device is to be used as shown in Figures 1 and 2 as a circuit breaker, and the contact 24 is arranged in engagement with the contact 25 and the current passing through the contact and also 90 through the winding of the magnet exceeds the predetermined strength, the armature will be attracted by the magnet and the contacts 24 and 25 will be separated to break the circuit.

In the construction illustrated in Figure 4, the contact 25 is reversed in position with relation to the tongue or vibrator and is disposed in operative relation with the contact 23 so that when the circuit is closed through 100 the winding of the electromagnet the attraction of the armature will serve to close the circuit by bringing the contact 23 into engagement with the contact 25. In this instance also the carrier 26 is adjustable to 105 vary the gap between the contacts 25 and 23.

In the modified construction illustrated

in Figures 1^a to 4^a the electromagnet 10^a is of the bar type having the core 11^a straight and extending axially through the winding or spool 12^a and preferably adjustable longitudinally therein and adapted to be secured at the desired adjustment by means of a collar 18^a fitted with a set screw 20^a. The extremity of the core is disposed adjacent to the tongue or vibrator 15^a which carries the contacts 23^a and 24^a of which the latter as shown in Figure 1 is arranged in operative relation with a contact 25^a carried by the adjustable support 26^a, so that in this instance the device constitutes a circuit breaker.

In Figure 4^a the parts are shown arranged for use as a circuit closer, with the contact 23^a arranged in operative relation with and adapted to be brought into engagement with a contact at the end of the magnet core.

From the above description it will be obvious that the device can be used not only as a circuit breaker and circuit closer under the conditions indicated but also as a relay and repeater and also and more particularly as a current limiter. As a current limiter the electromagnet and contacts are placed in a series with the circuit to be used in a desired service and on the current reaching a predetermined strength the contacts will be separated to open the circuit. Special attention is called to the fact that the current which can flow through the circuit thus limited cannot exceed the predetermined amount for which the apparatus has been adjusted and designed, and should the consuming device such as a lamp or otherwise connected to or included in the circuit require a greater amount of current the vibrator, consisting as indicated of a spring or diaphragm, will be caused to vibrate to effect the alternate opening and closing of the circuit in such a way that the mean effective current flowing through the circuit will be constant and equal to the maximum current for which the instrument was adjusted, and if the current consuming device therefore is a lamp or a group of lamps, they will be caused to grow dim or the light therein will be caused to flicker according to the characteristics of the spring vibrator, or diaphragm, and the contacts carried thereby.

As a relay and repeater the circuit into

which the current is repeated or relayed is usually connected in series with the contacts, the electromagnet being in series with the original or primary circuit, but obviously both primary and repeated circuits may be the same under certain conditions as will be readily understood.

The special advantages of the device herein-described reside in the simplicity and compactness of construction thereof, and the cheapness of manufacture together with the efficiency of the device, it being obvious that the instrument may be of small size with the number of parts limited to provide against any tendency to disarrangement or displacement. It will be noted that there are no pivots or other small moving parts likely to involve trouble or cause failure of the device by reason of displacement or otherwise, and moreover, there being no frictionally related moving parts, it is obvious that the durability of the device is practically unlimited.

In the construction illustrated in Figures 1-5 it is preferred, as shown to extend the armature terminal 28 inwardly into overlapping relation with the pole of the magnet, so as to be positively influenced thereby, regardless of the adjustment of the armature necessary to provide the required gap between the contacts to suit the strength of current which is to be carried without disturbing the normal relation of the contacts.

What is claimed is:—

A mechanism for the purpose indicated having an electro-magnet provided with pole pieces, a carrier mounted on one of the pole pieces, a yieldable vibrator extending from the carrier and being normally spaced from the other pole piece, said pole pieces being extended to dispose the vibrator in offset relation to the magnet, said carrier having an elongated slot, a securing means to pass through said elongated slot, and a flange extending from the carrier and engaging the adjacent pole piece to position the carrier.

In testimony whereof I affix my signature in the presence of two witnesses.

ELIAS ZARAGOZA.
